LOCK WASHER

Filed March 25, 1931

Inventor:
Carl G. Olson
By Oliver Cox & Morte
Atty.

UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

LOCK WASHER

Application filed March 25, 1931. Serial No. 525,094.

My invention relates generally to lock washers and particularly to improvements in lock washers of the pronged type formed from flat spring stock.

5 One of the primary objects of my invention is to provide lock washers of the pronged type having an improved pronged construction.

More specifically, it is an object of my invention to provide a lock washer from flat 10 spring stock having a plurality of radial prongs formed along one margin thereof, in which work engaging edges are positioned out of the plane of the washer stock by deflecting said prongs in a novel manner.

My invention contemplates the provision of radial prongs as above set forth, in which opposed margins thereof are deflected in opposite directions out of the plane of the 20 washer stock, the degree of deflection of said margins at the root of the prongs being greater than the degree of deflection at the opposite end of the prong, whereby to provide edges for lockingly engaging a work piece 25 clamped thereagainst.

It is a further object of my invention to provide a prong construction in which the opposed margins thereof are oppositely deflected or warped out of the plane of the washer 30 stock so as to render the outer end of the prong more resilient than the root thereof, and to present work engaging edges lying in planes spaced from and parallel with the body of the washer.

35 The foregoing and numerous other objects and advantages will be more apparent from the following detailed description when considered in connection with the accompanying drawings, wherein—

40 Figure 1 is a plan view of a lock washer constructed in accordance with the teachings of my invention;

Figure 2 is a transverse sectional view of 45 the lock washer taken substantially along the line 2—2 of Figure 1;

Figure 3 is a lock washer having external prongs constructed in accordance with the teachings of my invention;

50 Figure 4 is an enlarged transverse section

of one of the prongs of Figure 3 taken substantially along the line 4—4 thereof;

Figure 5 is a similar transverse sectional view taken along the line 5—5 of Figure 3.

Figure 6 is an end elevational view as 55 viewed along the line 6—6 of Figure 3; and

Figure 7 is a fragmentary enlarged perspective view of the lock washer of Figure 1 to more clearly disclose the structural characteristics of the locking prongs. 60

Referring now to the drawings more in detail wherein like numerals have been employed to designate similar parts throughout the various figures, it will be seen that one embodiment of my invention includes a lock washer designated generally by the numeral 10, Figures 1, 2, and 7. This washer includes an annular body portion 12 and a plurality of radial prongs 14 formed integral with and extending from the internal margin 70 of the body portion 12. This washer 10 is preferably formed from flat spring stock. 65

Particular attention is directed to the structural characteristics of the prongs 14. It will be noted that triangularly shaped marginal portions 16 of each prong are deflected in opposite directions out of the plane of the body portion 12. By deflecting these triangularly shaped flanges or leaves 16 in the manner disclosed, work engaging edges 18 are positioned out of the plane of the washer stock, and these edges lie in planes substantially parallel to the plane of the washer body. In order to provide the marginal leaves 16 as above described, it is necessary to impart a sharp or acute deflection to the margin of the prong at the root thereof and a considerably less angular deflection at the outer end of the prong. In other words, the free extremities 80 of the prongs are provided with flange portions which are more resilient than the flange portions at the root of the prong. 85

It may be stated that the prongs 14 which are formed integral with and extending from the body portion 12 each comprises three substantially triangular areas or sections. A central flat area is designated by the letter A, Figure 1, and the oppositely deflected marginal flanges 16 are positioned along the opposed margins of the sections A. In order 90

to position the edges 18 in planes spaced from and substantially parallel with the body portion 12, the inner or narrower portions of the triangular sections 16 must be subjected to a relatively sharp deflection with respect to the body portion, while the opposite or wider portion of said sections is subjected to a lesser angular deflection. This construction enables the root portions of the prong to vigorously oppose a clamping force tending to flatten same, and the wider portions of the flanges are adapted to more yieldingly or resiliently resist said clamping pressure. The invention is particularly adaptable for use in connection with securing soft materials against retrograde movement.

In Figures 3 to 6 inclusive I have disclosed a modified washer which I have designed generally by the numeral 10a. The prongs of this washer are constructed in a manner similar to the tapered prongs 14 of Figure 1. Numerals designating the various portions of the washer 10a correspond with the numerals designating equivalent structures of Figure 1. Figures 4 to 6 inclusive serve to more clearly illustrate the difference in degrees of deflection of the triangular marginal prong sections 16. Thus it will be seen that at the root of the prongs, the margins 16 are nearly perpendicular to the plane of the washer body. In Figures 5 and 6 it will be apparent that the degree of angular deflection with respect to the body portion decreases toward the outer or free end of the prongs.

From the foregoing it will be apparent that my invention contemplates the provision of a lock washer having prongs of improved practical construction. It will be apparent that each prong comprises substantially three elements, namely, the central flat section A and upwardly and downwardly deflected sections 16 which are also triangular in shape and which taper toward the root of the prong. The angle of deflection of these tapering portions with respect to the plane of the washer increases toward the root of the prong in such a manner that the edge 18 at the narrow part of the section 16 is positioned the same distance from the plane of the body portion as the portion of said edge at the wider section of the flange 16. In other words, the edges of the tapered deflected sections 16 are positioned in planes parallel with and spaced from the plane of the flat central section A throughout their entire length.

By having the deflected sections or flanges increasing in angularity toward the root so that the portion thereof adjacent the root is nearly perpendicular to the plane of the body 12 or central prong section A, a tooth construction is presented which is adapted to carry increased load at the root and which provides for increased elasticity or resiliency at its outer end. That is to say, the inner extremities of the prong are positive in lock-

ing action, while the outer ends thereof provide a spring locking action.

While I have disclosed a specific embodiment of my invention in the drawings, it will be clear that changes may be made without departing from the spirit and scope of the appended claims:

Having thus described my invention, what I claim as new and desire to secure by Letters Patent is:

1. A lock washer of flat spring stock including an annular body portion, and a plurality of prongs extending from one of the margins thereof, opposite margins of each prong being angularly deflected out of the plane of the washer stock so as to present work engaging edges lying in planes spaced from and substantially parallel to the plane of the washer body, said marginal portions being subjected to a greater angular deflection at the root than at the outer end of the prong, whereby to render the outer extremity of said edges more yieldingly resistant to clamping pressure than the portion of said edges adjacent the root of said prong.

2. A lock washer of flat spring stock including an annular body portion, and a plurality of prongs formed integral with and extending from one of the margins of said body portion, each of said prongs comprising a central substantially flat triangular section and triangular marginal sections deflected out of the plane of the washer body in opposite directions, whereby to present edges for locking engaging a work piece clamped thereagainst.

3. A lock washer of flat spring stock including an annular body portion, and prongs extending therefrom, the opposite margins of each prong being provided with triangularly shaped flanges angularly deflected out of the plane of the washer stock, the portions of said flanges adjacent the root of the prongs having a greater angular deflection with respect to the body portion than the portion of said flanges positioned at the opposite ends of said prongs.

4. A lock washer of flat spring stock including an annular body portion, and a plurality of prongs formed along one margin thereof, opposite margins of each prong being formed with flanges angularly deflected in opposite directions out of the plane of the body portion, the degree of angular deflection of each flange decreasing from the root to the free extremity of the prong, whereby to render the outer ends of the prongs more yieldingly resistant to clamping pressure than the roots thereof.

5. A lock washer of flat spring stock including an annular body portion, and a plurality of tapered prongs provided along the internal margin thereof, the opposite margins of each internal prong having triangular portions thereof deflected in opposite direc-

tions out of the plane of the washer stock, whereby to present work engaging edges spaced from the plane of said body portion.

6. A lock washer of the class described
5 formed from flat spring stock including an annular body portion, and a plurality of prongs formed along and extending from the outer margin of said body portion, said prongs being provided with substantially tri-
10 angular marginal flanges along opposite margins thereof which are oppositely deflected out of the plane of the washer body to position edges thereof out of the plane of the washer body for lockingly engaging a work
15 piece.

In witness whereof, I have hereunto subscribed my name.

CARL G. OLSON.
